MERCHANT MILL LAYOUT

Howard H. Talbot and Chester A. McDowell,
Pittsburgh, Pa., assignors to United Engineering & Foundry Company, Pittsburgh, Pa., a corporation of Pennsylvania

Application May 4, 1933, Serial No. 669,330

7 Claims. (Cl. 80—37)

Our invention relates to rolling mills, and particularly to a novel arrangement of rolling mill apparatus that is especially adapted for use in merchant mills. These mills are of the type in which a large variety of shapes and sections of rods and bars may be produced.

The principal object of our invention is to provide an arrangement of roll stands for the various successive operations of rolling rods and bars that permits flexibility of operation and adaptation of the speeds of the various roll stands in accordance with the speed with which material is delivered thereto.

A further object of our invention is to provide an arrangement that permits a fairly wide choice with respect to the sequence of operations in the finishing rolls of the mill.

In the construction and operation of merchant mills prior to our invention substantially all of the roll stands are driven by a single source of power, or the various roll stands are arranged in groups and each group is driven from a single source of power. A serious disadvantage in the operation of a mill of this character is the inability to vary the speed of certain of the roll stands with respect to the others in order to make allowance for variations in speed with which material is delivered thereto, or to vary the speed in accordance with the reduction in section or the size of the latter. Furthermore, if the finishing rolls are all driven from a single source of power, it is impossible to vary their relative speeds in accordance with desired operating conditions, or in accordance with the speed with which material is delivered thereto by the preceding roll stand.

In case the roll stands of finishing mills have been in alignment and driven by a single source of power, attempts have been made to use larger rolls progressively through the finishing mill in order to provide increasing peripheral speed of the rolls to approximately compensate for elongation of the metal stock. The disadvantages of this arrangement are that the axes of the rolls of adjacent mills are out of vertical alignment and the driving spindles therebetween are at an angle thereto and there is no possibility of variation in relative speeds of the roll stands in accordance with desired changes in operating conditions.

In accordance with our invention we arrange that all of the roll stands other than those of the usual roughing mill may be provided with individual driving motors whereby the speeds of each roll stand may be varied independently of

the speed of the roll stands of the same group, and also entirely independently of the speed at which the roughing rolls are operated.

The details of our invention will be described in connection with the accompanying drawing, in which the single figure is a somewhat diagrammatic view in plan of a rolling mill constructed and arranged in accordance with our invention.

A merchant mill comprises in general two roughing mills consisting of roll stands 1 and 2, 10 and 3 and 4, respectively, an intermediate mill comprising roll stands 5, 6, 7 and 8, and a finishing mill comprising roll stands 9, 10, 11 and 12.

The roll stands 1 and 2 of the first roughing mill are driven from a single driving motor 14 through suitable gear reduction mechanism 15. The second roughing mill consisting of roll stands 3 and 4 is provided with a single driving motor 16 which operates through suitable reduction mechanism 17.

In the intermediate mill each of the roll stands 5, 6, 7 and 8 is provided with its individual driving motor 18 that is connected thereto by means of reduction gear mechanism 19.

In the finishing mill, roll stands 9 and 10 are driven respectively by motors 23 and 24 through gear mechanisms 25 and 26, respectively. Each of the roll stands 11 and 12 is driven by a motor 27.

In the operation of the mill of our invention 30 billets are supplied from suitable billet skids 29 to a furnace 30 from which the heated billets are conveyed through pinch rolls 31 and a vertical shear 32 to a scale breaker 33 that is driven by a motor 34 through reduction gear mechanism 35. The metal or stock then passes successively through the roll stands 1, 2, 3 and 4 of the continuous roughing mill and is conveyed to the intermediate mill for passage through the roll stands 5, 6, 7 and 8 where further reduction occurs.

Following each of the roll stands 5, 6, 7 and 8 is a looper 36 which provides for any excess material between the adjacent pairs of intermediate rolls. The extent of this loop may be controlled by varying the speed of the motor of the succeeding roll stand, it being appreciated that increase in the speed of operation of the roll stand will reduce the extent of the loop preceding it. Also, the successive roll stands will be operated at progressively higher speeds to compensate for the elongation of the metal as it is reduced.

When the stock emerges from the intermediate roll stand 8, its shape and section are such that it may be supplied to the finishing mill to be passed through such of the rolls of the latter as are nec-

essary to place the stock in final or desired size and section. The number of roll stands of the finishing mill that are required to complete the rolling operation depends upon the size and section of the finished product.

If, for example, it is desired that the finished product be of relatively small section, the stock from the roll stand 8 will be passed through the roll stands 9, 10, 11 and 12 in sequence, as indicated in the drawing by the curved full line passing therethrough. By reason of the provision of ample space for looping the stock as it changes direction through the roll stands and by reason of the provision of individual driving motors for the finishing mill roll stands, the relatively small stock may be delivered at a comparatively high speed. For example, stock may be delivered from the finishing mill at a speed of approximately 3600 feet per minute. These results are obtained because it is possible to vary the speed of the individual driving motors to compensate for the elongation of the material as it is successively reduced in the several roll stands.

An alternative arrangement of the roll stands of the finishing mill is indicated in dotted lines. Such arrangement includes the transfer of roll stand 10 into endwise alignment with the roll stand 9, in which case it may be driven by the motor 23 for driving the roll stand 9. This arrangement includes also the transfer of roll stand 11 into endwise alignment with the roll stand 12, in which case the roll stand 12 will be driven by the driving motor 27 for driving the roll stand 12. A pass for the stock through this arrangement is indicated by dotted lines, the stock, after leaving the roll stand 8, passing through the roll stands 9, 10, 11 and 12 successively. When the stock traverses the latter path and is of intermediate section it may have a speed, for example, of 900 feet per minute.

When stock of relatively large section is produced it may not be possible to loop it in the manner described above in connection with sections of intermediate or small size, in which case the lengths will be passed through the mills separately and onto the floor plates of the mill or upon suitable conveyors, the trailing end being entered in the succeeding mill and the lengths rolled in reverse order. A speed of 500 feet per minute may be attained when lengths of stock are rolled in this manner.

The roll stands 9 and 11 or the roll stands 10 and 12 of the finishing mill are adapted to be interchangeable with vertical edges. When the latter are substituted, for example, for the respective roll stands 9 and 11 of the finishing train, it is not necessary to twist the stock between successive roll stands of the finishing mill in order to roll different sides of the stock and it is not necessary to station a man at alternate passes for the purpose of twisting the leading end of the stock in order that it may properly enter the succeeding mill.

When the finished product has emerged from the last roll stand of the finishing mill, it may be diverted to reels 38 to be coiled thereon. If the finished product is of such nature that it is desired to retain it in the form of rods or bars, it may be conveyed through a rotary flying shear 39 to a suitable hot bed 40 for cooling in the usual manner.

It will be noted that we have provided an arrangement or layout for a merchant mill that is extremely flexible in operation because of the ability to vary the speeds of the individual driv-

ing motors for the roll stands of the intermediate mill and the finishing mill. By this means the operation of the mill may be adapted to the character of the stock that is passing therethrough and with respect to the speed of the stock as it is delivered by the preceding mill in the series.

The arrangement of the roll stands of the finishing mill with their individual driving motors makes it possible to selectively vary the speeds of the respective roll stands and to select any desired combination of roll stands that may be necessary to reduce the stock to the shape and section that is desired for the finished product.

While the preferred operation of the mill has been described as comprising the bending of the material when the forward end thereof changes its direction and is fed into the succeeding roll stand, it will be appreciated that if desired the stock may be treated in desired lengths, the various lengths passing in a substantially straight line upon suitable conveyors and then passed in reverse order through the succeeding roll stand. Both of these methods of operation are in common use in rolling mills, and the adaptability of the mill for operation on material of this kind will be readily understood.

The foregoing and other advantages will be appreciated by those skilled in the art of constructing and operating rolling mill apparatus of the character of our invention.

We claim:

1. A rolling mill, comprising a roughing mill having a train of roughing rolls, an intermediate mill comprising a plurality of roll stands in alignment with said roughing mill, a finishing mill comprising a plurality of roll stands that are out of alignment with the intermediate mill and are arranged in pairs in tandem relation, the pairs being out of alignment with each other and thereby permitting the passing of metal through selected roll stands of said finishing mill, and a plurality of driving motors for said finishing mill, the speed of which motors may be varied approximately in accordance with the speed of metal delivered to the roll stands driven thereby.

2. A rolling mill comprising a roughing mill having a train of roughing rolls, an intermediate mill comprising a plurality of roll stands in alignment with said roughing mill, a finishing mill comprising a plurality of roll stands that are out of alignment with the intermediate mill and certain of said roll stands of said finishing mill being in tandem relation and the tandem roll stands being out of alignment with the other roll stands and thereby permitting the passing of metal through selected roll stands of said finishing mill, and a separate driving motor for each roll stand of said finishing mill, the relative speeds of which may be varied approximately inversely with the cross-section of the metal passing therethrough.

3. A rolling mill comprising a roughing mill having a train of roughing rolls, an intermediate mill comprising a plurality of roll stands in alignment with the roughing mill and a finishing mill comprising a plurality of roll stands out of alignment with said intermediate mill, pairs of said roll stands of said finishing mill being in aligned tandem relation for continuous operation and the pairs of tandem roll stands having separate driving motors for adjusting the relative speeds thereof and being out of alignment with each other to provide for looping of stock between said pairs.

4. A rolling mill comprising a roughing mill having a train of roughing rolls, an intermediate mill comprising a plurality of roll stands in alignment with the roughing mill and a finishing mill comprising a plurality of roll stands out of alignment with said intermediate mill, said roll stands comprising a plurality of sets, each set comprising a horizontal roll stand and a vertical roll stand in tandem and the sets of roll stands being 5 out of alignment with each other and provided with separate driving motors for providing relative driving speeds therefor.
5. A rolling mill comprising a roughing mill having a train of roughing rolls, an intermediate mill comprising a plurality of roll stands in alignment with the roughing mill and a finishing mill comprising a plurality of roll stands out of alignment with said intermediate mill and adapted to be disposed for operation by 10 pairs in tandem relation laterally spaced from each other or in spaced axially disposed relation.
6. A rolling mill comprising a roughing mill having a train of roughing rolls, an intermediate mill comprising a plurality of roll stands in alignment with the roughing mill, a finishing mill comprising a plurality of roll stands out of alignment with said intermediate mill and adapted to be disposed for operation by 15 pairs in spaced pairs operative in tandem or axially aligned relation and provided with individual driving motors certain of which are rendered inactive when the finishing stands are operated in axial alignment and certain of which 20 are adapted for double duty under such an arrangement.
